UNITED STATES PATENT OFFICE.

WILLIAM H. McCARROLL, OF WATERTOWN, NEW YORK, ASSIGNOR OF ONE-HALF TO JOHN B. TAYLOR, OF SAME PLACE.

SCREEN-PLATE FOR PAPER MANUFACTURE.

SPECIFICATION forming part of Letters Patent No. 643,521, dated February 13, 1900.

Application filed May 23, 1899. Serial No. 717,958. (No model.)

To all whom it may concern:

Be it known that I, WILLIAM H. McCARROLL, a citizen of the United States, residing at Watertown, in the county of Jefferson and

5 State of New York, have invented certain new and useful Improvements in Screen-Plates for Paper Manufacture; and I do declare the following to be a full, clear, and exact description of the invention, such as will enable others 10 skilled in the art to which it appertains to make and use the same, reference being had to the accompanying drawings, and to the letters of reference marked thereon, which form a part of this specification.

15 This invention relates to new and useful improvements in screen-plates used in paper-making machines, in which the screen-plates, made of thin metal, are adapted to be reversed and interchangeable, and being of thin material may be easily sawed and owing to the narrowness of the plates may be rigidly secured to girders of the screen-frame, thus preventing unnecessary vibration common in screens of ordinary use.

20 25 More specifically, the present invention resides in the provision of a paper-making machine in which the screen-plates are made narrow, of thin material, and secured along their longitudinal edges to girders by means 30 of metallic strips and tightening-bolts, the nuts of which bolts are preferably held in mortised recesses in the girders, thus allowing the bolts to be tightened as the nuts are held stationary.

35 30 To these ends and to such others as the invention may pertain the same consists, further, in the novel construction, combination, and adaptation of parts, as will be herein-after more fully described and then specifically defined in the appended claim.

40 My invention is clearly illustrated in the accompanying drawings, which, with the letters of reference marked thereon, form a part of this application, and in which—

45 45 Figure 1 is a perspective view of a screen-box, showing a portion broken away to better

illustrate the detailed construction of the removable plates. Fig. 2 is a cross-sectional view through the screen box and plates.

Reference now being had to the details of 50 the drawings by letter, A designates the outer wall of the box or frame, in which are disposed in rows the girders B, which have their under or lower edges tapered, as seen at B', so as to offer as little resistance as possible to 55 the passage of the stock underneath. Resting on said girders are the longitudinal edges of the screen-plates C, which are made thin, thus rendering them capable of being easily sawed. Resting on the edges of said plates 60 are the metallic bars D, with longitudinally-tapering edges. The ends of these bars are also beveled and rest against the beveled face of the cleat R. The walls of the girders are mortised out, as at E, for the reception 65 of the nuts F, into which the threaded ends G of the bolts G' are screwed. These bolts are passed through apertures in said bars and through apertures in the girders leading to said mortised recesses, whereby the bars may 70 be clamped against the edges of the screen-plates and securely hold the same to the girders.

From the foregoing it will be noted that when for any purpose the screens, or any of 75 them, become damaged in any way they may be easily replaced or reversed, which is a great advantage over the screens commonly in use, which are usually made of a thick metal, which previous to being sawed are 80 furrowed out and being wide are apt to vibrate, thus diminishing the work which the screens should perform.

Having thus described my invention, what I claim to be new, and desire to secure by 85 Letters Patent, is—

A screen-box for pulp-strainers, comprising in combination with the outer walls, a series of girders mounted in parallel rows in the ends thereof and provided with recesses, said 90 girders being disposed a slight distance above the bottom of the open box, a series of thin re-

versible strainer-plates resting on the upper edges of the girders, metallic clamping-bars having beveled edges and ends, and bearing on the edges of said plates, a beveled cleat 5 secured to the inner wall of the box and bearing against the beveled ends of the clamping-bars, bolts passing through the clamping-bars, and between the longitudinal edges of the screen-plates, and the tightening-nuts

seated in said recesses in the girders, all substantially as shown and described.

In testimony whereof I affix my signature in presence of two witnesses.

WILLIAM H. McCARROLL.
